Primary Examiner — Katrina A Betton(74) *Attorney, Agent, or Firm* — Kolisch Hartwell, P.C.**CLAIM**

We claim the ornamental design for a boat carrier, as shown and described.

DESCRIPTION

FIG. 1 is a perspective view of a boat carrier constructed in accordance with the present invention.

FIG. 2 is a front elevation view thereof. The rear elevation view is a mirror image of FIG. 2

FIG. 3 is a top plan view thereof.

FIG. 4 is a bottom plan view thereof.

FIG. 5 is a left side elevation view thereof; and,

FIG. 6 is a right side elevation view thereof.

The dash-double-dot-dash line(s) shown in the drawings are for illustrative purposes only and form no part of the claimed design.

The rear view of the design is a mirror image of the right side, so the rear view has been omitted.

The stippling and shading lines shown in the drawing(s) represent the approximate three-dimensional contour of the design, and are not intended to indicate surface decoration.

Portions of the boat carrier that are not shown in the drawing(s) form no part of the claimed design.
